UNITED STATES PATENT OFFICE.

CLARENCE C. FLEMING, OF AMITYVILLE, NEW YORK, ASSIGNOR TO EBERHARD FABER
PENCIL COMPANY, OF BROOKLYN, NEW YORK, A CORPORATION OF NEW YORK.

CRAYON-HOLDER.

1,151,933.

Specification of Letters Patent. Patented Aug. 31, 1915.

Application filed November 14, 1914. Serial No. 872,075.

To all whom it may concern:

Be it known that I, CLARENCE C. FLEMING, a citizen of the United States, residing at Amityville, in the county of Suffolk and 5 State of New York, have invented certain new and useful Improvements in Crayon-Holders, of which the following is a specification.

The object of this invention is to provide 10 a simple and cheap holder for crayons, by the use whereof the fingers may be adequately protected and given an agreeable gripping surface, and the crayon, which is fragile, may be protected, both as to its 15 point and as to its body, and may be utilized even when a substantial portion thereof has been worn away. In the production of colored crayons, it has been found that there is a variable shrinkage of material when 20 drying, due to which there is a lack of uniformity in the diameter of the finished crayons. For this reason, such a protecting and lengthening holder as I have devised should be, and in the present case is, provided with 25 means adapting it for use with crayons of varying thickness.

In the accompanying drawing, Figure 1 is a side view, partly in section, of my improved crayon-holder, with a crayon carried therein; Fig. 2 is a central sectional view, showing the crayon worn down to a short length; Fig. 3 is a plan view of the material of the holder; and Fig. 4 a transverse section on the line 4—4 Fig. 1, showing, however, a greater number of thicknesses in the holder than in said last-named figure.

A primary essential of a commercially practicable crayon-holder is that it shall be 40 cheap of production. Accordingly, in producing the holder under disclosure, I preferably employ paper 1, which may be fashioneded into a roll 2, as clearly illustrated in Fig. 4, one or both side edges of the material being preferably secured to the body of the roll, as by an adhesive. In so fashioning the material, the roll may be made of 45 two thicknesses or a greater number thereof, dependent upon its character and the de-

gree of stiffness to be given to the completed 50 roll. Such material is provided at suitable points with perforations 3, punched from the outside, so as to leave on the inside surface, for coaction with the crayon, 4, to be inserted in the holder, roughened portions 55 adjacent to such perforations, which, however, are yieldable, so as to effectively coact with the crayon. Preferably, these perforations will not extend over the entire area 60 of the sheet of material which is fashioned into the roll, but will terminate such a distance short of the outer side edge of the material as that the final covering, 5, of the holder shall be imperforate. By reason of the roughened interior of the holder, the 65 same is adapted for use with crayons of varying diameter, which may under slight pressure be moved freely within the holder, so that, for instance, the point of the crayon may, for its protection, be pressed back 70 within such holder and also be exposed when it is desired to use the same. Also, when the crayon has become worn, it may readily be pressed out of the holder, so that practically the last remaining portion thereof 75 may be used. The holder, being flexible and in intimate contact with the crayon, not only protects the same against breakage but in the event of accidental breakage can be relied upon to hold the severed parts of the 80 crayon together so as to permit the same to be utilized.

Having now described my invention, what I claim as new therein and desire to secure by Letters Patent is as follows:—

85 A crayon-holder, comprising a closed tube formed of two or more thicknesses of flexible material, provided with perforations forming protuberances for coaction with a crayon inserted within said tube and movable therein, substantially as set forth.

90 This specification signed and witnessed this 11th day of November, 1914.

CLARENCE C. FLEMING.
